UNITED STATES PATENT OFFICE.

LEILAMAE HARLOW, OF FORT WORTH, TEXAS.

DESIGN FOR AN ICE-CREAM CONE.

Application filed June 17, 1924. Serial No. 9,885. Term of patent 14 years.

To all whom it may concern:

Be it known that I, LEILAMAE HARLOW, a citizen of the United States, residing at Fort Worth, in the county of Tarrant and State of Texas, have invented a new, original, and ornamental Design for Ice-Cream Cones, of which the following is a specification, reference being had to the accompanying drawing, forming a part thereof.

The figure is a perspective view of the ice cream cone, showing my new design.

I claim:

The ornamental design for an ice cream cone, as shown.

In testimony whereof, I set my hand, this 12th day of June, 1924.

LEILAMAE HARLOW.
